EXPLOSIVE MOTOR

Richard Beckman, New York, N. Y.

Application August 17, 1928, Serial No. 300,221

5 Claims. (Cl. 123—55)

This invention relates to an improved explosive engine or motor adapted for general purposes but of peculiar fitness for use in the propelling of aircraft.

5 It is an object of the invention to provide a motor into the respective cylinders of which regulated quantities of fuel and air may be positively introduced at a ratio which may be varied in accordance with changes of atmospheric conditions, thus resulting in an increase in efficiency, an economical use of fuel, and a minimum amount of obstruction and wear of the working parts of the mechanism.

10 It is another object of the invention to produce an engine of the above-described character in which gas may be mixed and distributed to the respective power cylinders without being passed into or through the crank-case, thus avoiding a contamination of the fuel which would otherwise result from association with lubricants.

15 It is a further object of the invention to provide for the admission of gas to the power cylinders of the motor under such pressure and under such regulation as to dispense with the use of a special ignition system after the motor has once been started and warmed up, a sufficient compression being obtained to result in spontaneous combustion at or near the end of the compression stroke. The invention also includes means whereby the air and gas may be admitted to the power cylinders under such conditions as to prevent the ignition from becoming complete until the piston has substantially reached the end of

20 its stroke and the crank is at its dead-center.

An additional feature of improvement consists in so arranging the air-inlet and exhaust connections at the firing ends of the cylinders as to cause the exhaust gases to be rapidly cleared away by the entering fresh air, and to provide a copious volume of fresh air by which the single exhaust and air-inlet valve may be cooled immediately after each release of heated exhaust gases and during the following admission of atmospheric air to the cylinders, which air is slightly pre-heated by flowing over the parts of the mechanism which it cools as it enters.

The invention also provides novel means whereby certain parts of the mechanism may be vented through the inner ends of the power cylinders into the crank-case and whereby the crank-case may be vented through ports connecting the inner ends of the air-compression cylinders of the motor to the atmosphere.

Other novel features of the invention will be

come apparent as the mechanism is described in detail.

In the drawings illustrating the invention in its preferred form,—

Figure 1 is a rear face view of the engine, a part thereof at the left being omitted, and a part being indicated in section along a plane through the line 1—1 of Fig. 2.

Fig. 2 is a vertical section, the section through the cylinders being taken along planes passing through the lines 2—2 of Fig. 1, and the section through the mixing chamber and associated parts being taken along the plane passing through the lines 2—2' of Fig. 1.

Fig. 3 is a transverse section through one of the power cylinders along a plane passing through the line 3—3 of Fig. 2.

Fig. 4 is a timing diagram illustrative of the cycle of changed conditions which repeatedly occur in each of the power cylinders of the motor.

Referring first to Figs. 1 and 2, a motor embodying the invention comprises a plurality of power cylinders 20 mounted radially on a crank-case 21, within which rotates a crank-shaft 22 having a crank 23. In each cylinder is a piston 25 connected to one end of a pitman 26, and the several pitmen connect at their other ends to a common sleeve 24 journaled on the crank.

Preferably the source of gas supply for the power cylinders will comprise a mixing chamber 27 externally disposed with respect to and independent of the crank-case. Gasoline or other appropriate fuel may be fed to the mixing chamber by a suitable jet nozzle 28 to which, for best results, the fuel should be supplied at a rate proportional to the speed of rotation of the motor. This may best be effected by means of a fuel pump diagrammatically indicated at 29, which may be directly connected by means of suitable gearing to the motor shaft 22. Fuel fed to the pump through the supply pipe 30 may be conducted to the jet nozzle through the pipe 31 and admitted at a rate which may be regulated by any usual adjusting mechanism controlled by a hand-lever 32.

The air supplied to the mixing chamber will produce the most satisfactory results if fed there-to under pressure at a rate approximately proportional to that of the rotation of the motor. Such air may be fed to the mixing chamber from any appropriate source, but, in the preferred form of the invention herein disclosed, it is supplied by air compressors or superchargers directly connected with the crank of the motor. In the specific form of the invention disclosed

for purposes of illustration, the motor is represented as comprising nine power cylinders divided into two groups, one of four cylinders and one of five cylinders, by two air compressor cylinders or superchargers 33 located at points approximately opposite each other so that air will be drawn into one cylinder while it is being forced from the other to be conducted to the mixing chamber.

10 Each of the cylinders 33 is provided with a piston 34, which may be connected with the sleeve 24 by means of a pitman 35 corresponding with the pitman 26 of the power cylinders.

15 The admission and discharge of air to and from the supercharger cylinders may be controlled by valve mechanism of any suitable character. The air-intake port of each supercharger may be provided with a hood 36 (Fig. 1) having its opening facing towards the front of the engine and its valve will be so timed as to be opened during the suction stroke of its piston and closed during the compression stroke. The discharge outlet 37 of each supercharger cylinder may be provided with a spring-pressed valve 38, which 20 will permit air to be forced from the cylinder during the compression stroke of the piston through conduits 39 to the mixing chamber 27. The supercharger cylinders may also be provided with one or more auxiliary ports 40, said ports 25 being open to atmosphere and so positioned as to be uncovered by the outer end of the piston just before it reaches the inner end of its stroke. These ports 40 serve as a means of insuring the filling of the supercharger cylinders with air at 30 substantially atmospheric pressure just prior to the commencement of the outward movement of their pistons. The ports 40 also serve as a means for venting the crank-case in a manner which will hereinafter be described.

40 The invention includes means whereby gas may be fed from the mixing chamber to intake ports in the various power cylinders in succession, the connection to each cylinder being effective only throughout a period conforming substantially with that during which the intake ports are open. In the form of the invention herein disclosed, means is provided whereby the intake port of each cylinder is open only throughout the short period during which its piston is 45 at the inner end portion of its stroke, and the connection from the mixing chamber to each admission port is such as to be effective for the delivery of gas to each cylinder at each alternate stroke throughout the same period.

50 As indicated in Fig. 2, gas may be admitted to each power cylinder by means of a port, or preferably a series of ports 41, so positioned as to be uncovered by the outer end of the corresponding piston as it reaches the inner end portion of its stroke, indicated in broken lines at 41', Fig. 2, thereby permitting gas to enter the cylinder from 55 a surrounding passage 42 (Figs. 2 and 3) supplied with gas from the mixing chamber by a distributor mechanism constituting an important 60 feature of the invention, the preferred form of which will now be described.

65 The crank-case is provided with a housing to which connect radiating inlet conduits 49 leading to the respective cylinders 20 and communicating with their inlet ports 41 through the passages 42. Rotating with respect to the crank-case is a distributor 51 which receives the gaseous mixture 70 from the mixing chamber 27, through a conduit 47 (Fig. 2) leading to a chamber 46 in the crank-case housing, from which the gases flow into a

distributing chamber 54 from which as the distributor rotates the gases are directed successively into the inlet conduits 49, entering only the conduits of those cylinders in which the pistons are nearest the inner ends of their strokes, 5 so as to uncover the ports 41, while the other conduits 49 are cut off from communication with the distributing chamber and receive no gas.

10 In the construction shown, a housing comprising wall elements 43, 44, secured to an appropriate part of the crank-case, is divided by partition walls 45 into an inner annular chamber 46, connected by a conduit 47 with the mixing chamber 27, and an outer annular chamber 48 connected by the radially-disposed conduits 49 with the inlet 15 passage 42.

15 To afford a means of communication between the inner and outer chambers 46, 48, the partition walls 45 may be provided with a plurality of port openings 50 (Fig. 1).

20 The ports 50 may be controlled by the rotatable distributor 51, which may be secured to the motor shaft 22 and may have a portion 52 extending into the housing in a concentric sliding relationship with a portion of the partition wall 45. To 25 the outer surface of the ring 52 may be secured a pair of circumferentially spaced partitions 53 (Fig. 1) of dimensions such as to completely radially fill the chamber 48 and form a sliding fit with respect to the outer wall of the annular 30 chamber 48, thereby segregating a relatively small portion of this chamber from the remainder thereof to form the chamber 54.

25 Each of the pistons 53 may comprise a lug 55, which may be extended from the outer surface of 35 the ring 52, and a follower 56 between which and said lug a block of suitable elastic material 57 may be compressed into a fluid-sealing relationship with the walls of the annular chamber 48 by means of an appropriate adjusting mechanism 40 such, for example, as the stud 58 and nut 59.

30 The short portion of the ring 52 connecting the pistons 53 is provided with one or more ports 60 (Fig. 1), and the remainder of the ring 52 is made imperforate so as to close the adjacent ports 50, 45 and cut off communication between chambers 46 and 48. The number, size and spacing of the ports 50 and the number, size and spacing of the ports 60 should be such as to afford free communication at all times between the annular chamber 50 46 and the chamber 54 as the distributor 51, secured to the crank-shaft, is rotated with respect to the housing secured to the crank-case.

35 The pistons 53 on the valve ring 51-52 should be so related with respect to the crank 23 that 55 the chamber 54 will always be in communication with the conduit 49 of a cylinder the piston of which is at the inner end of its stroke, and the spacing of the pistons 53 should be such that the conduit of each cylinder will remain in communication with the segment 54 throughout the entire period during which the ports 41 are exposed at the outer end of the piston, so as to afford a means of communication between the chamber 54 and the cylinder.

40 It is important that the pistons 53 be of such dimensions circumferentially as to completely close the conduits 49 as they pass the same, so that said conduits will not form a by-pass 70 through which the gas mixture may escape from the chamber 54 to the remaining portion of the annular chamber 48.

45 One satisfactory means of exhausting products of combustion from the cylinders and supplying atmospheric air thereto, as indicated in Fig. 2, 75

comprises a single valve 61 normally held in closed relationship with respect to a port 62 by means of a spring 63. The movements of this valve may be controlled in any suitable manner, 5 as by means of a lever 64 connected by means of a rod 65 with a cam mechanism 65' (not fully shown) operated in a well-known manner through gearing connected to the crank-shaft 22. The gearing should be such as to impart a 10 single rotation to the valve-actuating cam for each two rotations of the crank-shaft, and the form of the cam should be such as to open and close the valve in accordance with the usual four cycle system as will be hereinafter described.

15 The air-inlet valves for the supercharger cylinders 33 may be controlled by mechanism similar to that providing for the control of the valves 61 of the power cylinders, except that the cams should be of such form as to open the inlet valve 20 of the supercharger cylinder at the beginning of each suction stroke of its piston and should close it at the end of each suction stroke.

25 Valve-operating mechanism of the above-described character is well known in the art and need not be specifically illustrated and described here.

If desired, the space just without the port 62 may be enclosed by means of a housing 66 having a rearwardly-disposed exhaust orifice 67 and a 30 forwardly-disposed air-inlet orifice 68. Such a housing constitutes a highly satisfactory means of expediting the scavenging of the cylinders from all exhaust gases at the end of the exhaust stroke and the introduction of pure atmospheric air at 35 the initial portion of the suction stroke of the piston. This is especially true when the engine is used as an aircraft motor, in which case the rapid flow of air into the orifice 68, which may, if desired, be deflected upwardly by baffles 69, 40 would have a tendency to pass rapidly over the port 62 into the exhaust orifice 67 and create a siphon effect adapted to clear the end of the piston of exhaust gases and carry them into the exhaust pipe connected with the orifice 67. If 45 all cylinders are connected with a common exhaust, this siphon effect at each cylinder end will be augmented since the exhaust of each cylinder will tend to produce a partial vacuum at the exhaust orifice 67 of each of the other cylinders which will aid in creating a flow of fresh air into the orifice 68 over the port 62 and out at the orifice 67. It will be apparent, therefore, 50 that before the piston commences its suction stroke all exhaust gases have been far removed 55 from the end of the cylinder and pure atmospheric air will be drawn into the cylinder during the suction stroke of the piston.

It is to be observed that the housing 66 affords a straight line passage from the air intake 60 to the exhaust outlet. The current of air passing through the housing may be broken up by baffles and deflecting walls so that it eddies into contact with the valve 61 and cools it more uniformly than is the case when there is no straight line 65 passage through the housing but a deflecting wall between the air inlet and exhaust orifices which precludes a straight line passage between them and directs the whole of the cold incoming current air directly against one side of the valve. 70 In the latter case the great difference in cooling of the two sides of the valve is liable to cause warping and improper operation if in fact it does not render any operation impossible. This is avoided by the present construction which, as 75 stated, provides a more uniform cooling.

A cycle of operations in accordance with which a motor equipped with the invention is well adapted for use is graphically represented in Fig. 4. As therein clearly indicated, starting with the piston of any power cylinder at the outer end of an exhaust stroke, the valve 61 remains open during a rotation of the crank through an arc of 110° during which fresh air is drawn into the cylinder. The valve 61 is then closed during a rotation of the crank through 10 an arc of 37° during which a partial vacuum is established in the cylinder. At this point communication has been established by the distributor between its chamber 54 and the conduit 49 of the cylinder, and the gas admission ports 41 15 commence to open on further movement of the piston. During a following rotation of the crank through an arc of 66° gas is admitted to the cylinder through the ports 41. Flow of gas during this period is due to three causes, that is, (1) 20 the partial vacuum which has been established in the cylinder, (2) the pressure established in the gas-mixing chamber 27 by the admission thereto of air under pressure, and (3) the centrifugal effect of the quantity of air which is 25 rapidly rotated about the engine shaft in the segmental gas chamber 54 by the pistons 53. Due to these three causes and the regulation of the admission of fuel and air to the gas-mixing chamber, definite quantities of gas mixture are 30 quickly introduced into the cylinder at each fuel-feeding stroke. After the admission of gas, the valve 61 remaining closed, the gases are compressed during the outward movement of the piston while the crank is being rotated to its 35 outer dead-center position. At some appropriate time prior to the end of this compression stroke, preferably within an arc of crank rotation of 25°, the gases are fired and are caused to expand and impart energy to the motor while the crank 40 rotates through an arc of 130°. The valve 61 is then opened and the products of combustion are permitted to escape through the port 62 while the crank rotates through an arc of 50° to its inner dead-center position and through 45 an additional 180° to its outer dead-center position. At the inner dead-center position the piston the second time uncovers the ports 41, but at this time the residual pressure of the gaseous products is in excess of the pressure in the inlet 50 passage 49, or the difference in pressures is insufficient to lift the check valve 72 (hereinafter referred to) so that no fresh gas is admitted to commingle with the exhaust gases. Thereafter the valve 61 remains open and the cycle is 55 then repeated.

During the initial starting and warming up of the engine, the explosion of the gases at an appropriate part of the cycle prior to the end of the compression stroke may be effected by 60 ignition mechanism of the dual high-tension type, comprising spark-plugs 70, 71, indicated on one of the power cylinders of the motor, connected with the usual source of energy and distributing mechanism (not shown). Due to the 65 uniformity with which the gas mixture may be admitted to the cylinders and to the degree of regulation of the mixture which may be attained, and the amount of compression which may be produced, it is found unnecessary to rely upon 70 the ignition system after the engine has once been thoroughly warmed up, the explosions thereafter taking place spontaneously. The manner in which the fresh air and gas mixture are admitted to the cylinders produces a sufficient de- 75

gree of stratification to avoid premature ignition, the complete ignition being delayed until the crank has reached its outer dead-center position, or approximately so. At the instant of introducing the rich fuel mixture through the ports 41 and close above the piston, there is stratified above this mixture the air previously drawn in; as the piston travels outward these two layers are compressed and as the compression proceeds they become mixed so that when the piston is near the outer dead center position the mixture is ignited. By thus delaying the mixture a premature explosion with resultant knocking is avoided. The admission of the rich fuel mixture under pressure into the chamber also has the effect of causing this mixture to become greatly agitated and to move rapidly about the cylinder from one point to another. This movement is transmitted to the air stratum above it so that by the time the combustible mixture is formed the gases composing it are in rapid motion and any ignition is almost instantaneously distributed throughout the whole body and the explosion becomes complete and substantially instantaneous throughout the whole body of the gases.

When the invention is applied to a motor of the form herein disclosed, having nine power cylinders arranged in the same plane, they will preferably be arranged for firing in the order 1—3—5—7—9—2—4—6—8, the power cylinders being regarded as being numbered consecutively and the supercharger cylinders being disregarded in the numbering.

It will be apparent that the ports 41 are exposed at the outer ends of the pistons not only at the fuel intake stroke but also during the exhaust stroke. This opening during the exhaust stroke is somewhat later than the opening of the exhaust valve 61, as a result of which the pressure in the cylinder has very materially decreased before the ports 41 are opened. However, in order to avoid a flow of exhaust gases into the conduits 49 leading to the gas distributor, each conduit may be provided with a suitable check valve, herein disclosed as a spring-pressed valve 72.

If desired, the length of the piston of each power cylinder may be made relatively short as compared with the length of its stroke, so that the ports 41 in the walls of the cylinder will be uncovered during each movement of the piston to the outer end portion of its stroke as shown in Fig. 2. This uncovering of the ports by the inner ends of the pistons permits any products of combustion which may be trapped within the space 73 between the check valve and the passage 42 to be vented through the ports 41 into the inner end of the cylinder and thereby permitted to pass into the crank-case.

In order that exhaust gases may not be allowed to accumulate in the crank-case, the latter may be vented by means of the ports 40 in the supercharger cylinders, the lengths of the pistons of which may be so proportioned with respect to the lengths of their strokes as to uncover the ports 40 when the pistons are moved to the outer ends of their strokes, thereby directly venting the crank-case to atmosphere.

By feeding measured quantities of fuel and air to the gas-mixing chamber at rates proportional to the speed of rotation of the motor, the latter may be caused to operate with a substantial degree of uniformity so long as atmospheric conditions are not changed. The invention, however, includes additional means of regulation whereby substantially the same degree of uniformity may

be provided for throughout widely varying changes of atmospheric density such as are experienced when using the motor as a means of propelling aircraft at widely varying altitudes. To adapt the motor for use under such circumstances the air-supply system may be provided with an exhaust valve or by-pass 74, which may be controlled by a suitable valve 75. If the mechanism has been adjusted to supply the motor with the proper mixture for use at high altitudes, with the by-pass closed, it would be supplied with too large a volume of air at low altitudes due to the greater density of the charge of air drawn into the cylinder through the port 62. At such times the proper mixture may be effected by opening more or less the valve 75 in the by-pass 74, thereby permitting part of the air supplied by the supercharger cylinders to escape to atmosphere and a smaller quantity to be admitted to the mixing chamber whereby to compensate for the charge of greater density drawn into the cylinder through the port 62.

Since the mixture of air and fuel to be fed from the mixing chamber to the distributor will be smaller when the by-pass is open than when it is closed, the conduit 47 may, if desired, be provided with a throttle valve 76, and this valve may be connected with the valve 75 in the by-pass by appropriate mechanism diagrammatically represented by the arms 77, 78 and connecting rods 79, so that the by-pass will be opened as the throttle valve is closed, and vice versa. If desired, the regulation of the throttle valve 76 and by-pass valve 75 may be effected automatically by means of a device sensitive to changes of atmospheric pressure. Such device, as indicated conventionally in Fig. 2, might comprise a lever 80, fulcrumed at 81 and having a motive device connected therewith consisting of a hollow diaphragm chamber 82 adapted to be flattened on increase of atmospheric pressure and a spring 83 adapted to expand the chamber on decrease of atmospheric pressure.

From the foregoing description it will be apparent that the invention provides a motor to which fuel and air may be supplied in a positive manner and under such regulation as to adapt it for a most economical consumption of fuel at high efficiency and capable of performing satisfactorily under widely varying conditions of temperature and atmospheric pressure. The fuel is kept entirely free from contamination by contact with lubricating oils, the valves are so disposed as to avoid over-heating, and the parts of the mechanism are so disposed as to thoroughly scavenge the cylinders after each combustion.

The invention is not intended to be limited to the specific form which has been selected for purposes of illustration but should be regarded as including modifications and variations thereof within the scope of the appended claims.

What is claimed is:

1. A fixed radial hydrocarbon engine comprising a plurality of radially-disposed power cylinders and air compression cylinders in the same radial plane, a crank and crank-shaft, pistons in the cylinders connected with the crank, a stationary gas-mixing chamber, conduits connecting the air compression cylinders with the chamber, means for feeding fuel to the chamber, and a gas distributor comprising a conduit connected with the chamber, conduits connected with the power cylinders, and relatively movable port-controlling elements by which the distributor conduit may be brought into successive commu- 70 75 80 85 90 95 100

nication with the conduits connected with the power cylinders, whereby an intermittent connection may be effected between the chamber and each of the power cylinders.

5 2. An engine having radial cylinders mounted on a crank-case, each cylinder having fuel inlet ports uncovered by the piston at full instroke, the crank-case having an annular fuel distributing chamber having ports communicating by 10 radial passages with said inlet ports, and a distributor entering said annular chamber and comprising partitions radially filling such chamber and circumferentially spaced apart to form a separate chamber communicating with two 15 of said radial passages coincidently with the uncovering of the corresponding inlet ports by the cylinder pistons, a source of gaseous fuel, and passages conducting such fuel to said distributor in the said separate chamber thereof 20 between said two radial pistons.

3. A four cycle internal combustion engine, each cylinder having at its outer end an air inlet and exhaust valve, and having fuel inlet ports uncovered by the piston at full instroke, a source 25 of gaseous fuel, and a rotating distributor turning at the same speed as the crank-shaft receiving fuel from such source, and directing it successively to the fuel inlet ports of the respective cylinders, a valve-operating means holding said 30 outer valve open both during the exhaust and on the ensuing suction stroke to draw in fresh air, the fuel admission through such ports occurring at the end of such stroke, and the compression on the next outer stroke, such valve-controlling means adapted at the end of the 35 next ensuing power stroke to maintain sufficient pressure of residual gases in the cylinder to prevent admission of fuel when said inlet ports are uncovered by the piston at the end of such power stroke, whereby while the distributor effects communication with the inlet ports of each cylinder 40 at each instroke of the piston, such fuel is admitted only at every alternate stroke.

4. A hydro-carbon engine comprising a plurality of power cylinders and air compression cylinders, a crank and crank shaft, pistons in the cylinders connected with said crank, a stationary gas mixing chamber, conduits connecting the air compression cylinders with said chamber, 50 means for feeding fuel to said chamber and a gas distributor comprising a conduit connected with said chamber, conduits connected with the power cylinders and relatively movable port controlling elements bringing the distributor

conduit into successive communication with the conduits connected with the power cylinders, whereby an intermittent connection may be effected between the chamber and each of the power cylinders, the gas admission ports in the power cylinders being so positioned as to be uncovered by their respective pistons as each piston is moved to the inner end portion of its stroke and thereby permit gas to flow from the distributor to the interior of the respective power 10 cylinders, check valves in the said conduits connecting with the power cylinders to prevent the flow of exhaust gases therethrough when the admission ports are opened during an exhaust stroke, the length of the power pistons being so 15 proportioned with respect to their lengths of stroke as to open the gas admission ports of said cylinders and afford a means of communication between the inner end of each cylinder and the distributor conduits connected therewith when 20 the corresponding piston is at the outer end portion of its stroke, thereby venting the part of the distributor conduit between the check valve and the cylinder port into the inner end of the cylinder, a crank case into which the inner ends 25 of the power and air compression cylinders open, the said air compression cylinders having ports in their walls so positioned as to be uncovered by the pistons during the outer end portion of the stroke of each, and thereby vent the crank 30 case to atmosphere.

5. An internal combustion engine having a rotatable crank shaft, a crank case, radial stationary cylinders circumferentially displaced about said shaft and a power piston in each of 35 said cylinders connected with said shaft, each of said cylinders having fuel inlet ports, an annular fuel receiving chamber adjoining said crank case, a distributor rotating at crank shaft speed about said receiving chamber, said distributor having an outer segmental opening and ports for 40 communicating with said chamber and a ported ring outside said segmental opening, and conduits connecting the ports of the last mentioned ring with the inlet ports of said cylinders respectively, said distributor directing the fuel successively to the fuel inlet ports of the respective cylinders, the rotating distributor being so related to the distributing ports as to make fuel supply communication with said ports of the 50 cylinders respectively at the in stroke end of the piston, while the said cylinder ports are uncovered by the piston.

RICHARD BECKMAN.
